UNITED STATES PATENT OFFICE

140,182

DESIGN FOR A PIN OR SIMILAR ARTICLE

John J. Sanduski, Omaha, Nebr.

Application November 6, 1944, Serial No. 116,157

Term of patent 3½ years

(Cl. D45—19)

To all whom it may concern:

Be it known that I, John J. Sanduski, a citizen of the United States and a resident of Omaha, in the county of Douglas and State of Nebraska, have invented a new, original, and ornamental Design for a Pin or Similar Article, of which the following is a specification, reference being had to the accompanying drawing, forming part thereof, in which:

Fig. 1 is a front elevation of a pin showing my new design;

Fig. 2 is a bottom plan view of the same as seen in Fig. 1;

Fig. 3 is a rear elevational view; and

Fig. 4 is a top plan view of my new design as seen in Fig. 3.

I claim:

The ornamental design for a pin or similar article, substantially as shown.

JOHN J. SANDUSKI.
